HEAT REGISTER OR SIMILAR ARTICLE

Carl Otto, New York, N. Y., assignor to The Dole Valve Company, Chicago, Ill., a corporation of Illinois

Application October 31, 1951, Serial No. 17,176

Term of patent 14 years

(Cl. D81—21)

To all whom it may concern:

Be it known that I, Carl Otto, a citizen of the United States and a resident of the city of New York, in the county of New York and State of New York, have invented a new, original and ornamental Design for a Heat Register or Similar Article, of which the following is a specification, reference being had to the accompanying drawing, forming a part thereof.

On the drawing:

Figure 1 is a front elevation view of a heat register or similar article, embodying my new design;

Figure 2 is a top plan view of the register; and

Figure 3 is an end view of the register taken from the right-hand side of Figure 2.

I claim:

The ornamental design for a heat register or similar article, as shown.

CARL OTTO.
